CIRCLE BALL GAME

Alexander H. Trumbull, Stratford, Conn.

Application August 5, 1935, Serial No. 34,778

9 Claims. (Cl. 273—1.5)

This invention relates to new and useful improvements in games and has particular relation to a circle ball game.

An object of the invention is to provide a portable game which can be easily set up and taken down and which may be played in various surroundings as on land, or ice, or in the water, as a bathing pool, at the beach or the like.

Another object is to provide a game apparatus of simple construction but embodying many novel features and which being adapted for use under widely differing conditions will have a general appeal.

Other objects and advantages will become apparent from a consideration of the following detailed description taken in connection with the accompanying drawings wherein satisfactory embodiments of the invention are shown. However, it will be understood that the invention is not limited to the details disclosed but includes all such variations and modifications as fall within the spirit of the invention and the scope of the appended claims.

In the drawings:

Fig. 1 is a side elevational view showing a simplified form of apparatus to be used in the present game;

Fig. 2 is a top plan view thereof portions of the base being omitted;

Fig. 3 is a plan view of the base of Fig. 1;

Fig. 4 is a plan view showing the layout of the playing field;

Fig. 5 is a plan view of a base for the device including a float so that it may be used for playing the game in the water;

Fig. 6 is an elevational view showing the float anchored in the water;

Fig. 7 is an elevational view similar to Fig. 1 but showing a more comprehensive apparatus;

Fig. 8 is a plan view of Fig. 7 the base being omitted;

Fig. 9 is a plan view showing a portion of the base of Fig. 7;

Fig. 10 is a plan view on an enlarged scale and showing the intermediate portion of the basket support;

Fig. 11 is a sectional view taken substantially along the line 11—11 of Fig. 10;

Fig. 12 is a detail elevational view on an enlarged scale showing a means to be manually actuated to project a ball for play;

Fig. 13 is a longitudinal sectional view at right angles to Fig. 12; and

Fig. 14 is an elevational view on an enlarged scale showing a detail.

Referring in detail to the drawings and at first particularly to Figs. 1 through 3, at 10 is generally indicated a base comprising a central casting or hub portion 11 having a vertically arranged internally screw threaded nipple 12 and having

horizontally arranged hollow portions 13 open at their outer ends as shown best in Fig. 1. To give the base greater effective area and thereby greater stability lengths of rods or pipe 14 are provided, and each has an end introduced into one of the hollow portions 13 and clamped or secured therein as by a set screw 15.

An upright 16 comprising one or more sections of pipe has its lower end screw threaded into the nipple 12. As shown, upright 16 comprises 10 pipe sections 17 and 18 connected by a nipple 19 although it is to be understood that the upright may comprise but one pipe section of the desired length or it may comprise a greater number of sections than shown. Preferably a plurality of 15 sections are used since then when the apparatus is taken down all the parts will be in short lengths for convenient portability.

Swivelly mounted on the upper end portion of the upright 16 is a support 20 to the opposite 20 sides of which are attached goal baskets 21 and 22. These are preferably similar to basket ball baskets and may comprise a circular frame 21a of flat strip iron secured to the member 11 by suitable screws and carrying the regulation mesh or net baskets 21 and 22 open at their lower ends. In addition to being turnable about the upright, support 20 is also slidable vertically thereon and to hold the support in position and maintain the baskets at the desired height a collar 23 is adjustable vertically on the upright and is held in the desired position by a set screw 24. On loosening the screw 24 collar 23 may be shifted to the desired position, and since the lower end of the support 20 rests on this collar the support and 30 the baskets it carries will be adjusted vertically with the collar. In the drawings a knob 25 is arranged at the upper end of upright 16 but its purpose is purely ornamental and it does not clamp the support 20, which with its baskets is 35 freely turnable about the upright.

The apparatus is preferably to be used on a court marked off as shown in Fig. 4 (although it is not confined to use with such a court) wherein 45 26 designates a border circle and 27 a goal circle, 45 relatively small with respect to the circle 26 and concentric with the latter. Diagonal lines 28 and 29 cross one another and divide the circles 26 and 27 and the space between such circles into four equal parts, and arranged on said lines within 50 the space between the circles 26 and 27 and equally spaced from one another are four relatively small guard circles 30, 31, 32 and 33. Preferably the respective end portions of the lines 28 and 29 are marked N, S, E, W, for North, 55 South, East and West.

When the apparatus is arranged on the court of Fig. 4 the center of the base 10 of the apparatus is located at the intersection of the lines 28 and 29, or the center of the large circles, as 60

shown. In this connection it is noted that preferably the border circle 26 is fifty feet in diameter while the goal circle 27 is approximately twelve feet in diameter, and each guard circle is 5 in the neighborhood of four feet in diameter, but these dimensions may be changed to suit conditions or as found desirable.

The rules and regulations as to fouls, penalties, playing time, ball used, and the like are or may be 10 the same as in regulation basketball. There should be five players on each team and all playing is done between the border and goal circles, and crossing of these circles is out of bounds. In order that each team may instantly recognize 15 which is its goal basket the baskets are preferably of different colors, although other means of marking as to distinguish them from each other may be used. At the start of the game 20 the team captains each choose a basket and the course of direction their teams shall take to complete a circle and thereby obtain a free shot at the basket as will later be explained.

One team plays clockwise and the other counterclockwise. At the half the teams change the 25 course of direction but may retain the same baskets. Preferably the game starts with jump-ball at the north guard circle 30, changing to east, south and west at the respective quarters of the game or to the guard circles 31, 32 and 33. The 30 players line up one man of each team in each guard circle and the fifth man of each team is behind his tapper at the jump ball position. There is no restriction, beyond the border and goal circles, on the movement of the player once 35 the ball is in play.

In playing the game each team attempts to 40 complete a circle by passing or dribbling the ball over five consecutive quarter lines, one team trying to do this in a clockwise direction around the court and the other team in the anti-clockwise direction, and when this is accomplished the team is entitled to a free shot at its basket from any selected one of the guard circles. The last player to touch the ball in completing the 45 circle is entitled to a free shot, and if the basket is made three points are scored for the team. The players shooting the basket must straddle one of the quarter lines, and it will be understood that to complete the circle the ball must pass over five quarter lines with the same team continuously in possession of the ball. A player may shoot 50 a basket at any time or from any position while the ball is in play before the circle is completed, and if successful his team receives one point. On fouls the position for shooting is the same as for the free shot but only one point may be scored for each foul. On the making of a basket the ball is dead and must be tapped from the jump ball position, and if at any time a 55 player makes a wrong basket the point or points are scored to the opposing team.

Since the support 20 is freely turnable about the upright 16 it will be apparent that a ball thrown at the basket but engaging the ring at 60 the mouth of the latter will cause the support and the baskets to turn with respect to the upright. Therefore, it will be understood that the positions of the baskets will be repeatedly changed as the game progresses, and that it is 65 important that the baskets be differently colored or have some other distinguishing feature so that each player may instantly recognize which basket he is trying for. Fig. 2 by the dotted lines suggests that the baskets may be moved relative to 70 the upright.

When the apparatus is not in use it may be disassembled and stored in a relatively small space since on loosening of the screws 15 the pipe sections 14 may be removed from the base piece or hub 11 and arranged in side-by-side relation. 5 Further, the support 20 and the baskets may be lifted off the upright 16 and the pipe sections comprising the latter may be disconnected and then will be relatively short and may be arranged in side-by-side relation. From this it will be seen 10 that when the apparatus is disassembled it will occupy a relatively small space for storage or shipment and is easily portable. The court of Fig. 4 is preferably laid out on a lawn or the like, although it will be appreciated that it might 15 be laid out on the frozen surface of a pond or swimming pool, on the bottom of a swimming pool, or in any other suitable location. The support with the baskets may be set in a swimming pool with the base 10 resting on the bottom of 20 the pool. The height of the baskets may be regulated as desired for the depth of water by using different lengths of pipe 17 or 18 or by adjusting the head 20 up or down on the pipe.

Figs. 5 and 6 show a base or support which 25 may be used when the game is to be played in a bathing pool or at the shore or the like and it is preferred not or undesirable to have it rest on the bottom. In such figures the base in the form of a float is generally designated 34 and includes 30 a series of planks 35 arranged in side-by-side relation and secured together as by cross bolts 36. Around the outer edge of the platform thus built up there is arranged a rubber pumper 37 to prevent the players from becoming injured by contact with the edge of the platform. To the underside of the platform there may be secured an air tight tank 38, and such tank may be provided with an annular flange through which pass bolts 39 securing it to the platform and additional 40 bolts 40 may pass through the tank and the platform and be secured with wing nuts 41 as shown.

A cross plank 42 is nailed or otherwise secured to the planks 35 and in turn has secured to it a casting or hub 43 adapted to receive the lower 45 end portion of an upright 44 corresponding with the upright 16 of Fig. 1. Upright 44 preferably has a sliding fit into the casting 43 and as shown is secured to the latter by a set screw 45. An eye 46 is welded or otherwise secured to the underside of the drum 38 and a cable 47 connects any suitable anchor 48 to said eye. The anchor limits movement of the base 34 preventing the latter from floating away. If this apparatus is used in a pool, then the various circles, etc. may be painted on the bottom of the pool. This device may also be used on land if desired as the base will rest on the ground. In this case the float may be removed as it is preferably attached so as to be readily disconnected from the 50 base. When used in the water at a beach or lake the court lines of course will be imaginary, and this may also be true in a swimming pool. When playing on the land a regulation basket ball is used, but when playing in the water it is preferable to use a waterproof ball as of rubber.

Figs. 7 through 14 disclose an apparatus to be used substantially the same as the apparatus of Figs. 1 through 4 but which is more complete and 70 is considered as a regulation apparatus. Referring now particularly to Figs. 7 through 14 at 49 is generally indicated a base from which extends an upright 50 on the upper end portion of which is turnably mounted a support 51 carrying a pair 75

of goal baskets 52 and 53 corresponding with the baskets 21 and 22 previously described.

Base 49 comprises a central member or hub 54 having a vertically extending tubular portion 55 to slidably receive the lower end portion of the upright 50 and the latter may be secured in the former on tightening of the set screw 56. A pair of angle members 57 are secured to the under side of the member 54 and to such angle members there are bolted or otherwise secured a series of straps 58 the outer ends of which are bent over and riveted or otherwise secured to a relatively larger diameter ring 59. A platform like disc 60 rests on the members 58 and comprises a part of the base being clamped between the base member 54 and the angle members 57. With the described construction it will be apparent that a large diameter light weight base is provided whereby the upright 50 will be held against tilting.

As here shown the upright 50 comprises a lower pipe section 61 and an upper section 62 the said sections being connected by a nipple 63. A collar 64 is secured to the upper portion of the upright as by a set screw 65 and in turn limits downward movement of the basket support 51 on the upright but does not interfere with turning movement of said support. Such support is shown as comprising a tubular portion 66 disposed about the upper end of the pipe section 62, and further comprises an upper annular wall 67 defining a receptacle 68 open at its upper end. According to the present plan the rings defining the entrances to the goal baskets are secured to the annular wall 67 of the support by suitable screws 52a.

The receptacle 68 is of such size as to partially receive the basketball 69 as shown in Figs. 7, 8 and 11 and means are provided for projecting or throwing the ball out of said receptacle to start the play. To this end the support 51 is so located with respect to the upright that the upper end of the upright projects slightly above the bottom wall of the receptacle 68. Within said receptacle about the projecting portion of the upright is a disc 70 and such disc is turnable about the upright and simply rests on the bottom wall of the receptacle 68 so as to be capable of turning with and relative to the support 51 as will later be more fully described, the friction of this disc on the bottom wall being reduced by providing it with a circular rib or boss 70a.

A strap-like member 71 extends across the upper end of the support 50 and has one end pivotally mounted on a pin 72 carried by a pair of ears 73 formed with or attached to the disc 70. From this it will be understood that the member 71 moves with the disc 68. Within the upper end portion of the upright there is arranged a cup-like member 73 at the upper end of which is a flange 74 resting on the upright and the lower end of which is substantially closed by a wall 75 having a centrally located opening therein for the passage of a rod 76. Within the cup 73 about the rod 76 there is arranged a coil spring 77, and such spring at its lower end bears against the bottom wall of the cup and at its upper end bears against a washer or stop 78 fixed to the rod. From this it will be understood that the spring 77 when compressed is normally tending to project the rod upwardly through the open end of the cup and into engagement with the member 71.

A casting 79 is located within the upright section 62 and is screw threaded to the lower end 75 of the rod 76 at 80 and such casting is provided

intermediate its ends with a slot 81 and at its lower end with a head-like portion 82 carrying pins or studs 83 projecting through slots 84 in opposite sides of the pipe section 62. Extending through and having bearing in opposite walls of the section 62 is a pin or bolt 85, and secured on said bolt at the outer sides of the pipe section are similar cams 86 and 87. To the bolt at one side of the cam 86 there is also secured a hand piece 88 which at its rear end portion is further secured to the cam at 89 and at its front end is provided with a handle or finger piece 90.

When the pipe sections 61 and 62 are connected to form the upright 50 a disc 91 is clamped between said sections and such disc has a centrally arranged opening through which passes a guide rod 92 connected with the lower end of the casting 79. Below the disc a nut 93 is threaded onto the rod so as to limit upward movement of the rod through the disc. In this connection it is noted that the bolt 85 above referred to passes through the slot 81 in the casting 79 and will not therefore interfere with vertical movement of the casting.

In the drawings the member 71 is shown as occupying a horizontal position extending across the open upper end of the cup 73. The cams 86 and 87 each include a curved wall 94 and a substantially straight wall 95. Assuming that the ball is in position on the member 71 and that play is to be started the proper person rocks the lever 88 downwardly to carry the cams to the dotted line position of Fig. 12. This releases the pins 83 from the cams and the spring 77 forces the rod 76 and the parts carried thereby upwardly. The upper end of the rod strikes the member 71 and throws the ball out of the recess 68 and into play. Upward movement of the member 71 under the influence of spring 77 is indicated by the dotted lines in Fig. 11.

To reset the ball projecting apparatus the lever 88 is turned in a clockwise direction imparting a similar movement to the cams and as the curved edges of the cams ride against the pins 83 the latter are forced downwardly and acting through the casting 79, rod 76 and washer 78 serve to compress the spring 77, it and the other mentioned parts being moved into the full line positions of Fig. 11, and is set ready to be again operated when the ball is next to be put in play.

Preferably the baskets 52 and 53 are differently colored so as to be readily distinguishable (although other distinguishing features may be used) and it will be apparent that as one or the other of the baskets are struck by a thrown ball the baskets will be turned about the upright. The disc 70 and the member 71 carried thereby may move with the support 51 and the baskets or the support and baskets may on occasion move relative to the disc. When a basket is struck a good sharp blow by a ball the baskets and support will be turned about the upright while the disc 71 remains stationary or is moved only slightly due to its inertia. Therefore, it will be impossible for a player to determine in advance the direction in which the ball will be thrown on release of the spring 77.

If the arrangement were such that the disc 70 always moved with the support 51 then the ball would always be thrown in the same direction with respect to the baskets so that players could determine in advance the direction in which the ball would be thrown. However, since the disc and member 71 will sometimes

move with the support 50 and at other times will not move with it there is no telling in advance the angle at which the ball will be thrown. This changing of the relative positions of the parts 5 is suggested by the dotted line positions of the member 71 in Fig. 10. This throw device for the ball may be used with the smaller stand construction of Figs. 1, 2, 3 and 5 if desired.

A member 97 is secured to the upright 50, and 10 such member as shown comprises a casting including a split tubular portion 98 embracing the upright and clamped against it at the desired elevation by a bolt 99, which, as shown in Fig. 14, partially enters a notch 100 in the upright 15 when the bolt is tightened whereby to positively prevent vertical movement of the member along the upright. Formed integrally with the tubular portion of the member 97 is a radially extending piece 101 providing a step whereby to enable a 20 player to reach high enough to deposit the ball in the receptacle 68. If desired, the upper surface of the step 101 may be roughened as shown best in Fig. 9.

Member 97 also includes a disc or flange-like 25 portion 102 to which are connected the upper ends of radial deflector springs. As shown these comprise coil springs 103 and the lower end of each such spring is connected with a piece 104 to which is also connected the upper ends of a 30 pair of the springs 105 which have their lower and outer ends connected with the ring 59. The arrangement is such that the springs are maintained under tension so that when the ball drops or is thrown onto the springs the ball will be 35 thrown outwardly onto the playing field. If the springs are omitted a ball when thrown at a basket may drop to the ground closely adjacent the upright 50 and become a dead ball requiring that it again be projected from the receptacle 68 40 into play. When the springs are used, if the ball drops onto them, it will bounce out into the playing field. In certain instances it may not be necessary to double the number of springs adjacent the ring 59. For example, if the ring is 45 of relatively small diameter the outer or lower ends of the springs will not be unduly spread apart because of the increase of the diameter of the ring 59 with respect to the diameter of the ring-like part 102 to which the upper ends of 50 the springs are connected. However, where the ring 59 is of large diameter it is preferred to double the number of springs adjacent the ring so that there will be no likelihood of a ball passing through the springs.

55 Having thus set forth the nature of my invention, what I claim is:

1. In a game apparatus, an upright, a support on and turnable about the upright, a pair of goal baskets on said support, said support including a portion for supporting a playing ball, and means operating with a trigger-like action for projecting the ball from the support for play and loosely mounted on the support so as to throw the ball at unknown angles.
2. In a game apparatus, an upright, a support on and turnable about the upright, a pair of goal baskets on said support, means on and turnable with and relative to the support and including a horizontally pivoted member adapted to have a 60 playing ball disposed on it, spring means for forcing said member upwardly about its pivot to

throw the ball into play, and trigger-like means controlling operation of said spring means.

3. In a game apparatus, an upright, a support on and turnable about the upright, a pair of goal baskets on said support, means on and turnable with and relative to the support and including a horizontally pivoted member extending across the upper end of said upright and adapted to have a playing ball disposed on it, a rod vertically movable through the upper end of said upright, a spring for projecting said rod upwardly to have it engage said member and force it upwardly to throw the ball into play, and cam means operable by a rotary movement to draw said rod downwardly against the action of the 15 spring and thereafter on further rotary movement release the rod for actuation by the spring.

4. In a game apparatus, an upright, a support on and turnable about the upright, a pair of goal baskets on said support, means on and turnable with and relative to the support and including a vertically movable member extending across the upper end of said upright and adapted to have a playing ball disposed on it, a rod vertically movable through the upper end of said upright, a spring for projecting said rod upwardly to have it engage said member and force it upwardly to throw the ball into play, and cam means on said upright at the outer side thereof below said support and operable by a rotary 20 movement to draw said rod downwardly against the action of the spring and thereafter on further rotary movement release the rod for actuation by the spring.

5. In a game apparatus, a base, an upright 35 supported by the base, a support on the upper portion of said upright, a goal basket on said support, and inclined deflector means between the base and upright and adapted on being engaged by a ball to throw the same outwardly with respect to the upright.

6. In a game apparatus, a base including an annular part, an upright supported by the base, a support on the upright, a goal basket on said support, a member secured to the upright above the base, and tensioned deflector springs extending at an incline between said member and the annular base part and adapted on being engaged by a ball to throw the same outwardly away from the upright.

7. In a game apparatus, an upright, a support turnable about said upright, a pair of goal baskets on said support, and a ball support and projector on said upright and first support for throwing a ball into play from the first support.

8. In a game apparatus, an upright, a support turnable about said upright, a pair of goal baskets on said support, a ball support and projector on said upright and first support for throwing a ball into play from the first support, and means 60 whereby said projector is operable to throw the ball at different angles relative to the support and baskets.

9. In a game apparatus, an upright, a support turnable about said upright, a pair of goal baskets on said support, a horizontally pivoted member movable with and relative to said support and adapted to have a ball placed thereon, and spring operated means for snapping said member upwardly about its pivot to throw a ball into play.

ALEXANDER H. TRUMBULL.
